L. A. ANDERSON.

CORN DRIER.

APPLICATION FILED APR. 8, 1916.

Patented Mar. 27, 1917.

Inventor

L. A. ANDERSON

By *Watson E. Coleman*

Attorney

UNITED STATES PATENT OFFICE.

LEVI ARCHIE ANDERSON, OF ROCK FALLS, IOWA.

CORN-DRIER.

1,220,309.

Specification of Letters Patent. Patented Mar. 27, 1917.

Application filed April 8, 1916. Serial No. 89,966.

To all whom it may concern:

Be it known that I, LEVI ARCHIE ANDERSON, a citizen of the United States, residing at Rock Falls, in the county of Cerro Gordo 5 and State of Iowa, have invented certain new and useful Improvements in Corn-Driers, of which the following is a specification, reference being had to the accompanying drawings.

10 This invention relates to certain improvements in corn driers and it is an object of the invention to provide novel and improved means wherein a support is provided for a removable carrier and whereby said support is provided with means coacting with the carrier for maintaining the means applied to the carrier in substantially a perpendicular position.

The invention consists in the details of 20 construction and in the combination and arrangement of the several parts of my improved drier whereby certain important advantages are attained and the device is rendered simpler, less expensive and otherwise 25 more convenient and advantageous for use, all as will be hereinafter more fully set forth.

The novel features of the invention will hereinafter be definitely claimed.

30 In order that my invention may be the better understood, I will now proceed to describe the same with reference to the accompanying drawings, wherein is disclosed a view in perspective of a drier constructed 35 in accordance with an embodiment of my invention, with a single carrier applied thereto.

As disclosed in the accompanying drawings, 1 denotes a plurality of uprights preferably four in number, each pair of uprights being operatively connected by the braces 2 whereby side frames are afforded, and the corresponding uprights 1 of the frames are connected by the horizontally disposed bars 3.

40 Each bar 3 of a vertically aligned series of bars has coacting therewith a superposed bar 4 arranged in predetermined spaced re-

lation relative thereto and whereby a guideway is afforded through which is adapted 50 to be extended an extremity of a carrier 5, said carrier 5 being angular in cross section and preferably flat in plan, whereby it will be perceived that when the carrier is operatively positioned, the same is effectively 55 held against turning movement so that the upstanding penetrating members 6 carried by the carrier 5 may be maintained in a vertical direction in order to position the ears E affixed thereto in a corresponding arrangement. It is to be understood that the penetrating members 6 are adapted to be inserted within an end of the ear or cob thereof.

It will also be readily observed that the 65 carriers 5 are capable of sliding movement longitudinally of the bars 3 with which they are operatively engaged which is particularly desirable in order to separate the tested ears from the remainder. Furthermore it will be readily understood that by 70 having the carrier 5 readily removable, the ears may be properly applied thereto before the same is rested upon the bars 3 whereby the labor incidental in applying 75 the ears to be dried is materially facilitated.

It has also been found that with a drier arranged in accordance with my present invention, a requisite circulation of air is permitted and assures any moisture in the 80 cob settling to the lower end thereof and thereby effectively preventing the seed germs being affected.

From the foregoing description it is thought to be obvious that a drier constructed in accordance with my invention is of an extremely simple and comparatively inexpensive nature and is particularly well adapted for use by reason of the convenience and facility with which it may be 90 assembled, and it will also be obvious that my invention is susceptible of some change and modification without material departure from the principles and spirit thereof and for this reason I do not wish to be understood as limiting myself to the precise

arrangement and formation of the several parts herein shown in carrying out my invention in practice.

I claim:

- 8 A drier comprising a supporting member including a plurality of substantially longitudinally aligned bars, additional bars imposed upon and spaced relatively to certain of the first named bars to afford 10 guides, substantially flat carriers adapted

to be rested upon the bars, an extremity of each of the carriers being insertible through a guide, and penetrating members extending from the carrier.

In testimony whereof I hereunto affix my 15 signature in the presence of two witnesses.

L. ARCHIE ANDERSON.

Witnesses:

J. F. HOLDEN,
W. O. PRESCOTT.
